UNITED STATES PATENT OFFICE.

ALFRED A. WOHLAUER, OF NEW YORK, N. Y.

DESIGN FOR AN ELECTRIC-LIGHTING GLOBE.

Application filed May 23, 1921. Serial No. 471,979. Term of patent 3½ years.

To all whom it may concern:

Be it known that I, ALFRED A. WOHLAUER, a citizen of the United States, residing at the city of New York, county of Bronx, and State of New York, have invented a new, original, and ornamental Design for an Electric-Lighting Globe, of which the following is a specification, reference being had to the accompanying drawing, forming a part of this specification, and in which—

Figure 1, is a view in elevation of an electric lighting unit, showing my new design; and,

Fig. 2, is a top plan view thereof.

The entire globe is made of one piece of glass, having either the side, top or bottom portion of the central body portion of clear glass.

What I claim is:

The ornamental design for an electric lighting globe substantially as shown and described.

ALFRED A. WOHLAUER.
